UNITED STATES PATENT OFFICE.

DANIEL D. NOFZIGER, OF SWANTON, OHIO.

GRAIN-SEPARATOR.

No. 798,971.

Specification of Letters Patent.

Patented Sept. 5, 1905.

Application filed January 31, 1905. Serial No. 243,482.

To all whom it may concern:

Be it known that I, DANIEL D. NOFZIGER, a citizen of the United States, residing at Swanton, in the county of Fulton and State of Ohio, 5 have invented a new and useful Grain-Separator, of which the following is a specification.

This invention relates to grain-separating devices for threshing-machines, and it may be 10 described as being an improvement on the device for which Letters Patent of the United States No. 745,371 were issued to myself on the 1st day of December, 1903.

The invention also consists in part in the 15 novel construction and improved arrangement and combination of parts, which will be hereinafter fully described, and particularly pointed out in the claims.

In the accompanying drawings has been 20 illustrated a simple and preferred form of embodiment of the invention, it being, however, understood that no limitation is necessarily made to the precise structural details therein exhibited, but that the right is reserved to 25 any changes, alterations, and modifications to which recourse may be had within the scope of the invention and without departing from the spirit or sacrificing the efficiency of the same.

30 In said drawings, Figure 1 is a longitudinal vertical sectional view of a portion of a threshing-machine constructed in accordance with the principles of the invention. Fig. 2 is a detail top plan view of a portion of the separating-grate and related parts. Fig. 3 is a 35 perspective detail view of one of the bars of the separating-grate detached. Fig. 4 is a detail plan view of the vibratory grate 4.

Corresponding parts in the several figures 40 are indicated by like characters of reference throughout.

As in the prior patent referred to above, a revoluble beater and picker 1 is provided, the same being located in rear of the usual threshing-cylinder 2 and concave 3, but separated from the latter by means of a vibratory grate 4, which latter is supported by links 4^a between the concave and a cross-piece 5, upon which the bars 6, constituting the separating-grate 7, are bolted or otherwise suitably secured. The location of the grate-bars with 45 relation to the picker and beater is precisely as in my previous Letters Patent above referred to; but the points of the grate-bars are 50 in the present instance connected with a transverse bar 8, extending between the sides 9 of

the casing of the threshing-machine. The grate 4 is composed of a plurality of fish-backs 4^b, connected by rods 4^c, which are suitably spaced apart, so that separation of grain 60 may take place freely at this point. In the present instance the curved grate-bars are provided with laterally-extending prongs or tines 10 10, which are curved in conformity with the curvature of the grate-bars and which 65 extend laterally from the sides of the latter, being, however, sufficiently spaced apart to provide the necessary clearance for the passage of the fingers 11 of the rotary beater 1.

12 and 13 represent, respectively, the front 70 and the rear straw rack or carrier, said racks being provided in the usual manner with bottoms composed of inclined slats 14, between which grain may escape, and with fish-backs 15, serving to feed the straw in a rearward direction. 75

16 is a rock-shaft having arms 17 and 18 supporting, respectively, the rear end of the front straw-rack and the front end of the rear straw-rack. The front end of the front straw-rack 12 is supported by means of links, one of which is seen at 19.

20 is a rock-shaft having arms, as 21, supporting the rear end of the rear straw-rack 13 and also provided with arms 22, supporting 80 the rear end of a fluted grain-board 23, the front end of which is supported by means of links, one of which is shown at 24.

Suitably supported by means of links 25, 90 above the bottom of the threshing-machine casing, is a grain-pan 26, which receives the grain that is separated at the various stages of operation and which includes a sieve 27, through which the clean grain may pass to the point of discharge. 95

28 is a driven shaft having a pulley 29, which is connected by a pitman 30 with an arm or crank extending from the rock-shaft 16. Another arm extending from said rock-shaft is connected by a pitman 31 with the 100 grain-pan 26, to which latter a reciprocatory movement will thus be imparted.

The vibratory grate 4 may be driven in any suitable manner, as by a link or pitman 19^a, connecting with a supporting-link 19 of the 105 rack 15, said link being obviously disposed exterior of the casing, which latter is provided with arcuate slots for the passage of the pivotal pins.

The revoluble picker and beater may be 110 driven in any suitable manner and at any desired rate of speed, it being understood, how-

ever, that the rate of speed of said picker and beater shall be sufficient in order to enable the best results to be obtained. The direction of rotation of the picker and beater is reverse to 5 that of the cylinder. The reciprocatory parts of the device are driven in the relative directions indicated by darts.

In the operation of this device the straw as it passes from between the cylinder and concave passes over the vibratory grate 4, which gives it an opportunity of loosening up and causes a considerable separation of grain to 10 take place before the straw is engaged by the beater. The arms of the latter, which is operated at considerable speed, will engage the straw and toss it violently in a rearward direction onto the rack 12, causing the straw to 15 be thoroughly disintegrated and the grain to be thoroughly separated therefrom. Owing 20 to the peculiar construction of the grate-bars, movement of any portion of the straw in the direction of the cylinder is positively prevented, and what is of still greater importance the coaction of the beater-arms and the 25 grate-bars provided with the prongs or tines 10 will tend to rend the straw asunder, thus insuring a thorough separation of the grain.

Having thus described the invention, what is claimed is—

- 30 1. In a grain-separator, a separating-grate comprising a plurality of curved bars having laterally-extending tines curved in conformity with the curvature of said bars.
2. In a grain-separator, a cylinder and concave, a stationary separating-grate curved re- 35

versely to the concave and spaced apart from the latter, and a grate supported for vibration between the concave and the stationary grate.

3. In a grain-separator, a cylinder and concave, a stationary separating-grate spaced from the concave and comprising a plurality of curved bars having prongs or tines, a picker and beater having radially-extending arms operating in the clearances between the tines, 45 and a grate supported for vibration between the concave and the stationary grate.

4. In a grain-separator, a pair of straw-racks, a link-supported grain-pan, a grain-board supported between the grain-pan and the rear straw-rack, a rock-shaft having arms supporting the rear end of the front straw-rack and the front end of the rear straw-rack, a rock-shaft having arms supporting the rear ends of the grain-board and the rear straw- 55 rack, links supporting the front ends of the grain-board and the front straw-rack, a driven shaft having a crank-wheel, a pitman connecting the latter with an arm extending from the rock-shaft between the straw-racks, and a pit- 60 man connecting one of said straw-racks with the grain-pan.

In testimony that I claim the foregoing as my own I have hereto affixed my signature in the presence of two witnesses.

DANIEL D. NOFZIGER.
